(57) **CLAIM**

The ornamental design for a purse organizer, as shown and described.

DESCRIPTION

FIG. 1 is a front and top perspective view of a purse organizer, showing my new design;

FIG. 2 is a rear, left, and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, and top perspective view thereof, illustrated in an alternate configuration; and,

FIG. 10 is a perspective view of the purse organizer when a component of the purse organizer is removed from the purse organizer.

The stippling used in the drawings indicates a contrast in appearance. The broken lines in the drawings depict portions of the purse organizer that form no part of the claimed design.
